UNITED STATES PATENT OFFICE.

JOHN A. PRITCHARD, OF CHICAGO, ILLINOIS, ASSIGNOR, BY MESNE ASSIGNMENTS, TO
STRUCTURAL GYPSUM CORPORATION, OF NEW YORK, N. Y., A CORPORATION OF
DELAWARE.

BUILDING CONSTRUCTION.

Application filed May 27, 1921. Serial No. 473,103.

To all whom it may concern:

Be it known that I, JOHN A. PRITCHARD, a citizen of the United States, residing in Chicago, in the county of Cook and State of Illinois, have invented an Improvement in Building Construction, of which the following description, in connection with the accompanying drawings, is a specification, like characters on the drawings representing like parts.

This invention relates to a building construction and more particularly to the roof and floors thereof when made of reenforced plastic material, such as gypsum, concrete and the like.

The invention has for its object to provide a novel construction of slab and particularly a preformed slab, which may project beyond its support any desired or required distance and have the slab anchored to its support without extending the steel frame of the building. To this end, the slab, preferably a preformed slab, is provided with one or more openings extended from the bottom of the slab, preferably to the top thereof, and is further provided with an anchoring rod which is embedded in the slab and is extended across said opening or openings, and is arranged with relation to the latter so as to permit the anchoring rod to be engaged with an anchoring device or member attached to the purlin or other support, when the slab is laid in place upon the latter.

These and other features of this invention will be pointed out in the claims at the end of this specification.

Fig. 1 is a view of a portion of a building embodying this invention.

Figs. 2 and 3, details of a core and core cover to be referred to.

Fig. 4, a plan on an enlarged scale of a portion of the end slab shown in Fig. 1, and

Fig. 5, a section on the line 5—5, Fig. 4.

In the present instance, I have shown a sufficient portion of a floor or roof embodying the invention to enable it to be understood. The floor or roof is preferably composed of a plurality of individual or precast end slabs *a* and intermediate slabs *b*, each provided with longitudinally extended

reenforcing members or wires 10 and transverse reenforcing members 12.

The intermediate slabs *b* are supported at their ends by intermediate purlins 13, only one of which is shown, and the end slabs *a* are supported at one end upon an intermediate purlin 13 and between its ends by an end purlin 14, which latter may be separated from the intermediate purlin 13 by the desired or normal distance or span between adjacent intermediate purlins.

The end slabs *a* are made of greater length than the span between the purlins 13, 14 so as to project beyond the end purlin any desired or required distance to form the overhanging portion 16.

The end slab in accordance with this invention is provided with one or more holes or openings 17, preferably extended through it from top to bottom and removed from the outer end of the slab at such distance as will bring the holes or openings over the end purlin 14, which is effected by placing in the mold (not shown) in which the end slab is formed, suitable core blocks, which are located away from the inner end of the mold a distance substantially equal to the distance between the end purlin 14 and the next adjacent intermediate purlin 13. In the manufacture of the precast slab, the transverse reenforcing members 12 are positioned in the mold as are also the longitudinal reenforcing members 10, and the outer end transverse reenforcing member 12 is preferably made as a rod and is located in the mold a distance from the inner end of the latter which is substantially equal to the length of the span between the end purlin 14 and the next intermediate purlin 13.

The longitudinal reenforcing members 10 are connected with the outer end transverse reenforcing member 12, which may be effected as shown by coiling the reenforcing members 10 around the outer end transverse member 12 and extending the outer free ends of the members 10 beyond the outer member 12 so as to form a reenforce for the overhanging portion 16 of the end slab. When the reenforcing members have been properly positioned in the mold, a core block 18 of the desired size and provided with a slot 19, see Fig. 2, is placed in

the mold so as to straddle the outer end re-enforcing member 12.

After the core block 18 has been placed in position, gypsum or other plastic material is poured or cast into the mold to form the slab. To facilitate removal of the core block from the cast slab, after the latter has set sufficiently, the core block may be provided on its outer surface with a layer of grease or as preferred with a layer of paper 20, which may be in the shape of a box or envelope open at its top and bottom and of a size to fit the core block as shown in Figs. 2, 4 and 5. The box or envelope 20 is provided in its sides with slots 21 which register with the slot 19 in the core block.

When the plastic material has set sufficiently, the core block 18 is readily removed and the paper cover 20 remains in the opening. The end slab thus made is laid upon the purlins 13, 14 and anchoring devices 22 are adjusted on the purlin 14 so as to enter the openings and engage the outer transverse reenforcing member 12, which constitutes an anchoring member for the longitudinal reenforcing members 10. The anchoring devices 22 may and preferably will be made as herein shown and each consists of a metal member provided with a slot 23 to permit the metal member to be engaged with the flange 24 of the purlin and be erected thereon. The metal member 22 is provided with a finger or projection 25 which is designed to extend upwardly between the anchoring rod 12 and the inner end of the opening 17 as shown in Figs. 4 and 5.

After the end slab α has been placed in position on the purlins 13-14, the holes or openings 17 in the slab are filled with plastic material 26 to provide the end slab with a smooth unbroken upper surface, as represented in Fig. 1. The longitudinal reenforcing members 10 of the slabs in longitudinal alignment and supported by the intermediate purlins 13, may be connected together, as represented in Fig. 1, to form a continuous longitudinal reenforcement extended from end purlin to end purlin and

anchored to the latter, while providing the end slabs with overhanging portions 16 which project beyond the end purlins.

Claims:

1. In a building construction, in combination, an end purlin, an anchoring device erected upon said end purlin, a slab of plastic material supported by said purlin and having an opening into which said anchoring device projects, and provided with an anchoring member extended into said opening and cooperating with said anchoring device.

2. In a building construction, in combination, an end purlin, an anchoring device erected upon said purlin, a slab of plastic material supported by said purlin and having an opening into which said anchoring device projects, and provided with an anchoring member extended into said opening and cooperating with said anchoring device, and a reenforcing member for said slab connected with said anchoring member and extended beyond the same into the end portion of said slab.

3. In a building construction, in combination a precast slab of plastic material provided with a longitudinal reenforcement and with a transverse reenforcement, and having an opening located near one end of the slab and cooperating with the transverse reenforcement to uncover the same and form an anchoring member within the slab, a support for the end of the slab and an anchoring device erected upon said support and extended into said opening and engaged with said transverse reenforcement.

4. In a building construction, in combination a precast slab of plastic material provided with an opening and having an anchoring member embedded in the slab and extended into said opening, a support for said slab and an anchoring device connected with said support and extended into said opening and engaged with the anchoring member embedded in said slab.

In testimony whereof, I have signed my name to this specification.

JOHN A. PRITCHARD.
